TUMBLER

George W. Emmert, Winnetka, Ill.

Application November 1, 1954, Serial No. 32,886

Term of patent 7 years

(CL D36—8)

FIG. 1

FIG. 2

FIG. 3

FIG. 4

Fig. 1 is a perspective view of a tumbler showing my new design;

Fig. 2 is a top plan view thereof;

Fig. 3 is an elevational view; and

Fig. 4 is an elevational view partly in cross-section, illustrating the interior thereof.

The characteristic feature of my design resides in the combination of a double-wall tumbler with a transparent lip portion, opaque lower outer shell, and transparent fluted inner shell, as shown.

I claim:

The ornamental design for a tumbler, substantially as shown and described.
